UNITED STATES PATENT OFFICE.

THOMAS DIXON PARKIN, OF CHELMSFORD, ENGLAND, ASSIGNOR TO RADIO CORPORATION OF AMERICA, A CORPORATION OF DELAWARE.

RADIO SIGNALING APPARATUS.

Application filed December 2, 1921, Serial No. 519,311, and in Great Britain January 31, 1921.

The object of this invention is an improved circuit which may be used for actuating a calling or alarm device or for recording signals. The circuit may be adapted for use in measuring frequencies.

According to this invention a receiver is coupled preferably by means of an iron cored telephone transformer to the grid-filament circuit of a three electrode valve in series with the anode of which is a tuned oscillatory circuit and to a point in the inductance of this circuit is connected through the coil of a relay the anode of a second valve in the grid-filament circuit of which is an inductance coupled to the first named inductance. The coupling between the two inductances together with the leak produced by the first valve is so adjusted that the second valve does not normally generate oscillations, but is kept steadily on the verge of oscillation when no signals are being received. On the incidence of waves of the predetermined frequency the currents resulting therefrom are magnified by the first valve and thus a difference of potential is set up on the two sides of the oscillatory circuit in which large currents therefore circulate. Consequently the second valve generates oscillations, the energy to support the oscillations being drawn from the high tension battery and the relay is actuated to give the alarm.

Upon cessation of the signal the adjustment of the coupling and the leak contributed by the first valve are sufficient to quench the oscillation set up by the second valve, the current through the relay falling to its original value and ceasing to operate the relay.

In some cases the anode circuit of the second valve does not include a portion of the inductance of the oscillatory circuit, but the former arrangement is to be preferred.

Preferably a galvanometer is included in series with the relay coil for the purpose of noting the change of current.

The invention is illustrated by the accompanying drawing in which Fig. 1 embodies the invention and Fig. 2 shows a modification.

In Figure 1, V, V', are the two valves. In the grid circuit of valve V is the secondary of a transformer T, the primary of which is connected to the receiving system. CL is

an oscillatory circuit connected between the anode of the first valve and the high tension battery HT. Coupled to the inductance L is a second inductance L' connected between the grid and the filament of the valve V. The anode of this second valve is connected through the coil of a relay R and through a galvanometer G to an adjustable point P in the inductance L. When a sufficient current flows through the coil of relay R owing to the oscillation set up by valve V a bell B in a local circuit is sounded.

The arrangement shown in Figure 2 differs from that of Figure 1 in that the anode of valve V' instead of being connected to an adjustable point in the inductance L is permanently connected to the side of circuit CL which is remote from the anode of the first valve. This circuit is not arranged to be on the verge of oscillation. On the incidence of waves of predetermined frequency the currents due to the signal are magnified by the first valve and large currents circulate in the tuned circuit CL. These currents induce a difference of potential at the terminals of L' which is rectified by the second valve, the consequent increase of mean anode current being sufficient to work the relay.

These circuits may be used as recording circuits for wireless telegraph signals, especially continuous wave signals, a recorder of known type being substituted for the bell B.

Signals are received and in the case of continuous waves are heterodyned to a predetermined frequency and applied to the terminals of transformer T. The circuit CL is tuned to the predetermined frequency or in the case of spark signals to the spark frequency. The relay will now follow as previously described the signals of the Morse code and will operate the local circuit containing the recorder.

Either circuit may also be used as a frequency meter. The inductance L being known, the condenser can be calibrated in frequencies. If an alternating difference of potential be applied to the terminals of transformer T and the condenser be adjusted, a maximum current will flow through the galvanometer G when the applied frequency equals the frequency to which LC is tuned.

Having described my invention, what I claim is:

1. The combination of two three-electrode valves one of which is on the point of self-oscillation when no oscillations are impressed on it, means for applying incoming oscillations to the grid circuit of one valve, an oscillatory circuit adapted to be tuned to a desired frequency connected to the anode of that valve and connected to the grid circuit of the second valve by means of an adjustable tap and a relay coil connected between the oscillatory circuit and the anode of the second valve.
- 10 15 2. The combination of a three electrode valve, means for applying incoming oscillations to the grid of said valve, an oscillatory circuit connected in the anode circuit

of said valve, a second three electrode valve having its grid circuit connected to said oscillatory circuit by means of an adjustable tap and a relay coil in the anode circuit of said second valve whereby the second valve is in a condition of self-oscillation only when oscillations are impressed on the first valve. 20 25

3. The combination of two three-electrode valves, means for applying incoming oscillations to the grid circuit of one valve, an oscillatory circuit comprising an inductance and a capacity in parallel, means for coupling the grid circuit of the other valve to said inductance, a connection from the anode of the last mentioned valve to an adjustable point on said inductance and a relay cooperating with said connection. 30

THOMAS DIXON PARKIN.
